VALVE RECEIVING TUBING CLAMP

John W. Mullins, P.O. Box 20524,
Oklahoma City, Okla. 73120

Filed Nov. 3, 1969, Ser. No. 19,921

Term of patent 14 years

Int. Cl. D23—01

U.S. Cl. D23—40

FIG. 1

FIG. 2

FIG. 3

FIG. 4

FIG. 5

FIG. 6

FIG. 1 is a side elevational view of a valve receiving tubing clamp embodying my new design;

FIG. 2 is another side elevational view taken from a position 90° from that of FIG. 1;

FIG. 3 is a perspective view thereof;

FIG. 4 is another perspective view of the dual end slotted service valve line clamp in an inverted position from that shown in FIG. 3;

FIG. 5 is a top plan view of FIG. 2; and

FIG. 6 is a bottom plan view of FIG. 2.

The broken line representation of a valve and a line in FIG. 1 and is for purposes of illustration only.

I claim:

The ornamental design for a valve receiving tubing clamp, substantially as shown and described.
